Monteparo et al., "Bottle," Unpublished Design U.S. Appl. No. 29/553,626, filed Feb. 3, 2016.

Primary Examiner — Ian Simmons*Assistant Examiner* — Keith Frank(74) *Attorney, Agent, or Firm* — Andrus Intellectual Property Law, LLP(57) **CLAIM**

The ornamental design for a bottle, as shown and described.

DESCRIPTION

FIG. 1 is a top front perspective view of our new and ornamental design for a bottle;

FIG. 2 is a bottom front perspective view thereof;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the drawings showing the bottle illustrate the portions of the bottle that form no part of the claimed design.

1 Claim, 6 Drawing Sheets(56)
